UNITED STATES PATENT OFFICE.

PAUL G. ZIMMERMANN AND BORIS V. KORVIN-KROUKOVSKY, OF KEYPORT, NEW JERSEY, ASSIGNEES, BY MESNE ASSIGNMENTS, TO HEALEY-AEROMARINE BUS COMPANY, INC., A CORPORATION OF NEW YORK.

WING-NOSE RADIATOR.

Application filed April 1, 1924. Serial No. 703,359.

The invention relates to airplanes, and particularly to the radiator for cooling the cooling water of the engine driving the propeller. The object is to provide a radiator which operates in an improved manner, besides being advantageously incorporated in the machine with respect to the functions of support and flight. The invention comprises a radiator disposed in the nose of an aerofoil. The radiator is sectional and flexibly articulated, and other features relate to the construction of the sections, and devices for holding the sections in place and together and for permitting removal and replacement of any section.

In the accompanying drawings illustrating the invention:

Fig. 1 is a side elevation having an intermediate portion broken out, showing the engine and its cooling system in relation to a wing having the radiator in its nose;

Fig. 2 is a fragmentary plan view of the wing with intermediate portions of the part shown broken out for economy of space;

Fig. 3 is a vertical transverse section on an enlarged scale through the forward part of the wing and the radiator, dotted lines illustrating how the retaining bands may be opened;

Fig. 4 is a section on the irregular line 4-4 of Fig. 3, through the adjoining ends of two of the radiator sections; and

Fig. 5 is a fragmentary front elevation at the same region.

The engine of the airplane is seen at 2 in Fig. 1, and 3 is the hot-water pipe leading from the engine water-jacket, and 4 is the return pipe leading back from the radiator.

These two pipes connect with a duplex leg 5 of streamline form, which extends upward to the forward part of the wing 6. A septum 7 divides this leg into passages 3^a and 4^a forming continuations of the pipes 3 and 4, and the leg may be prolonged upwardly through the wing to form a filling neck 8.

The forward spar of the wing is indicated at 9, and the nose of the wing in front of the spar is provided with a longitudinally extending recess defined by suitable back and bottom seat members 10, 11 against which the radiator 12 forming the nose rests.

The radiator extends longitudinally of the nose in opposite directions from the

leg 5, the half of the radiator included in Fig. 2 being shown as extending as far as the position of the gasoline tank 13.

Each half of the radiator is composed of a plurality of separate sections 14. Fig. 2 indicates the one half as being composed of two sections, though this may be varied. The sections will be understood as being substantially larger than is actually shown in Fig. 2, where the limited space has necessitated shortening up the wing by breaking out a large part of its area. The several sections of the radiator are flexibly and separably connected with each other and with the central section 14^a forming an enlargement of the leg 5, this section 14^a having two chambers 15^a and 16^a which communicate, respectively, with the two passages of the leg.

As clearly illustrated in Figs. 3 and 4 each radiator section is made with front and rear water chambers or tanks 15 and 16 and an interposed cellular core 17 having upwardly and rearwardly inclined air-passages 18 therethrough, with narrow water spaces between the air spaces through which the water finds its way from the chamber 15 to the chamber 16. The cores are advantageously made of "cartridge tube" construction. The sections are of wing-nose form, and the rear tank is shaped to seat against the members 10, 11. At the adjoining ends of the sections, including the central leg section 14^a, are flexible, telescopic circulatory joints comprising necks 19 projecting from the water chambers of one section, and inwardly flanged sockets 20 in the end walls of the chambers of the other section. Gaskets 21 around the necks compressed between the beveled flanges of the sockets and the wall at the base of the necks make the joints water-tight, yet the construction is one that permits of sufficient angular movement of the sections relatively to each other to conform to and give with the aerofoil without straining the radiator.

The sections of the radiator are drawn together by means of fastenings consisting of bracket lugs 23 fixed to the upper and lower sides of the sections at the ends, and bolts 24 passed through perforations in the adjacent limbs 25 of these brackets and equipped with nuts 26.

The sections 14 are held in place by upper

and lower flexible metal straps 27, 28, the rear ends of which are fixed, respectively, to the upper and lower parts of the aerofoil. These straps embrace the radiator sections 5 at the ends of the sections, and the forward ends of the complementary straps are formed with interfitting eye loops 29 through which are passed fastening pins 30. As shown in Fig. 5 one of these pins may 10 be employed with advantage to serve the adjacent retaining straps of two sections, and it will be kept from coming out by a cotter pin 31. The straps overlie the basal limbs 32 of the brackets 23 of the fastenings 15 which draw the sections together, these limbs having out-turned ends 33 so that the straps are confined laterally between said ends and the limbs 25. This engagement of the retaining fastenings, which are fixed to 20 the body of the aerofoil, with projections or recesses on the radiator sections consolidates the general structure and resists relative displacement longitudinally of the wing, or laterally with respect to the straps. 25 Fig. 3 indicates in dotted lines how the straps can open when unfastened so as to permit the removal of one or more of the sections. Such removal may be for the purpose of replacement and repair, or for the 30 purpose of reducing the radiating capacity. The latter purpose can also be attained by opening the radiator and plugging circulatory connections between sections, so as to block one or more of the sections out of circuit. 35 It will be perceived that with our radiator the cooling is dependent on the angle of attack rather than on speed alone, and that thereby the cooling conforms more truly to 40 the varying needs of the engine. As the angle is flattened the region of greatest vacuum effect above the nose shifts rearward, and thereby the flow of air through the air passages of the core is affected. 45 What we claim as new is:

1. In an aerofoil, an engine-cooling radiator comprising a front water chamber, a rear water chamber and an interposed core having upwardly inclined air-passages extending upwardly therethrough, the whole being embodied within and of a form with the nose of the aerofoil.
2. A radiator occupying the nose of an aerofoil and composed of separate sections 50 having water chambers and interposed cores of cellular construction providing upwardly extending air-passages, with flexible tele-

scopic joints between the water chambers of adjoining radiator sections, substantially as set forth.

3. An aerofoil, and a radiator of flexibly articulated sections extended along the nose of the aerofoil.

4. A wing-nose radiator composed of separate sections having front and rear water chambers and interposed cellular cores with upwardly extending air passages, flexible joints adapted to connect the water chambers of adjoining sections in circuit, and means for securing the sections together.

5. A wing-nose radiator composed of separate sections having front and rear water chambers and interposed cellular cores with upwardly extending air passages, circulatory connections between the water chambers of adjoining sections, fastenings for drawing the sections together, flexible retaining bands secured to the aerofoil to embrace the sections, said bands engaging with said drawing fastenings, and fastenings separably connecting the ends of said bands.

6. In combination with an aerofoil having its nose recessed, a radiator of wing-nose form seated in the recess of the nose and forming the nose of the aerofoil, said radiator composed of separate sections having upwardly extending air passages therethrough, circulatory connections between the sections, and means for securing the sections, substantially as set forth.

7. An aerofoil having a longitudinally recessed nose, and a radiator lying in said recess composed of separate, removable, flexibly connected sections, with upwardly extending air passages therethrough.

8. An aerofoil having its nose longitudinally recessed, a radiator seated in said recess, flexible bands secured to the upper and lower portions of the aerofoil to embrace and hold the radiator in place, and fastenings separably connecting the ends of said bands.

9. In combination with an aerofoil having its nose recessed in front, a radiator composed of separate sections seated in said recess, retaining straps secured to the aerofoil and embracing the sections, and projections on the sections with which the straps are engaged preventing displacement, substantially as set forth.

PAUL G. ZIMMERMANN.
